UNITED STATES PATENT OFFICE.

ALBERT L. COX AND WILLIAM U. GOODWIN, OF STRATFORD, OKLAHOMA.

PLOW-ANVIL.

No. 889,206.

Specification of Letters Patent.

Patented June 2, 1908.

Application filed July 19, 1907. Serial No. 384,624.

To all whom it may concern:

Be it known that we, ALBERT L. COX and WILLIAM U. GOODWIN, citizens of the United States, residing at Stratford, Oklahoma, have invented certain new and useful Improvements in Plow - Anvils, of which the following is a specification:

This invention consists of a novel form of anvil designed for special work, as well as to 10 perform the functions of the common types of anvils which are at the present time in use. As is well known, it is customary to sharpen the throat of a plow-share upon an anvil, after the said share has become worn out at 15 this portion.

The aim of the present invention specifically is to provide a construction of anvil which facilitates the sharpening of plowshares as above mentioned, said construction not interfering whatever with the use of 20 the anvil in performing the various operations which are usually accomplished under ordinary conditions of service of a device of this nature.

For a full understanding of this invention 25 and the merits and advantages thereof reference is to be had to the following detail description and the accompanying drawing, in which

Figure 1 is a perspective view of an anvil 30 embodying the invention and Fig. 2 is a top plan view thereof.

Corresponding and like parts are referred to in the several figures by the same reference 35 characters.

In the carrying out of the present invention there is no considerable modification of the general construction of the anvil, as compared with those which are now in common 40 use.

The anvil embodying the invention comprises the usual bed 1 from one end of which projects outwardly the horn 2, the opposite end of the bed 1 extending laterally from the 45 body of the anvil as customary. The bed 1 is formed with the polygonal opening 3 and the circular opening 4 at the end thereof opposite that from which the horn 2 extends, the opening 3 being provided to facilitate 50 operations which may be performed by what is commonly called the "hardy", a tool utilized for metal cutting purposes. The opening 4 is advantageously used for punching or bolt threading operations.

The essential feature of the present invention resides in the provision in the upper sur-

face of the bed 1 of a recess 5 which is preferably formed by cutting away the bed so that the bottom of the recess is substantially flush with the top surface of the horn 2. The recess 5 is of peculiar outline, its inner edge being arranged substantially diagonal with respect to the parallel side edges of the bed, whereby a diagonal shoulder 5^a is provided 60 extending entirely across the bed 1 of the 65 anvil situated adjacent to the horn 2 above described.

The formation of the recess 5 is advantageous as it facilitates the operation of sharpening the throat of plow-shares, making the anvil a very desirable tool for use in repair shops. The arrangement of the shoulder 5^a is such that when a plow-share is disposed upon the anvil, preliminary to the sharpening operation, the edge of the throat 70 plate may be readily positioned in line with the said shoulder 5^a as the side bar of the share will abut with one of the side edges of the bed of the anvil, and thus form a guide 75 adapted to hold the share in proper position 80 as it is being operated upon. Not only will this bar serve the function above mentioned but it will admit of more readily moving the share into the desired position initial to the sharpening operation above mentioned.

The provision of the recess 5 at the point 85 described with respect to the bed of the anvil, and its peculiar formation, will not detract in any way from the advantageous use of the anvil for the purposes for which it is generally 90 employed.

It will be understood that the detail construction of the invention may be slightly modified in carrying out the same and in order to accomplish the best results so far as 95 the practical adaptation of the invention may be concerned.

In the sharpening of a plow share it is the common practice for the smith to hold the share so that its edge to be sharpened will 100 substantially coincide with an edge of the anvil so that the hammer may draw out the share as thin as desired by blows so directed that the face of the hammer will be at an angle to the face of the anvil. By placing the 105 edge of the share proximate to an edge of the anvil the hammer will not forcibly strike against the anvil directly. That portion of the share where the point verges into the main cutting edge, and known as the throat, 110 is the part most difficult to sharpen, and in order to secure the aforesaid advantage of an

edge engagement with the anvil for the throat and at the same time secure greater ease and stability in holding the share upon the anvil I have provided the shoulder 5^a as before set forth. In Fig. 2 I have indicated diagrammatically in dotted lines the position assumed by a share while the throat is being sharpened. In said figure *a* indicates the point, *b* the main part of the share, *c* the throat, and *d* the bar or landside. It will be noted that the bar *d* lies against the edge 1^a of the anvil, greatly assisting in holding the implement in place, and thus bringing the throat in line with the edge of the shoulder 5^a. This type of anvil is especially designed for repair shops, and it will be understood that the precise angle between the edge 1^a and the shoulder 5^a will be determined according to the general form of the plows to be repaired.

Having thus described the invention what is claimed as new is:—

An anvil for special work comprising a body at the upper portion of which is provided the anvil bed, a horn extending from one end of the bed, the upper surface of said bed being provided with a recess at the end adjacent to the horn, said recess having its inner edge arranged diagonally with respect to the side edges of the anvil bed and extending entirely across the bed, whereby the diagonal shoulder 5^a is provided, for the purpose set forth.

In testimony whereof we affix our signatures in presence of two witnesses.

ALBERT L. COX.

WILLIAM U. GOODWIN.
